UNITED STATES PATENT OFFICE

125,005

DESIGN FOR A SCARF

Harry Rosenbaum, Denver, Colo.

Application November 28, 1940, Serial No. 96,909

Term of patent 7 years

To all whom it may concern:

Be it known that I, Harry Rosenbaum, a citizen of the United States, residing at Denver, in the county of Denver and State of Colorado, have invented a new, original, and ornamental Design for a Scarf, of which the following is a specification, reference being had to the accompanying drawing, forming part thereof.

The figure is a plan view of a scarf, showing my new design.

I claim:

The ornamental design for a scarf, as shown.

HARRY ROSENBAUM.
